UNITED STATES PATENT OFFICE

JOHN S. FIELDING, OF TORONTO, CANADA.

DAM, RETAINING-WALL, OR BREAKWATER.

No. 813,695.

Specification of Letters Patent.

Patented Feb. 27, 1906.

Application filed January 16, 1905. Serial No. 241,845.

To all whom it may concern.

Be it known that I, JOHN S. FIELDING, of the city of Toronto, in the county of York and Province of Ontario, Canada, have invented certain new and useful Improvements in Dams, Retaining - Walls, and Breakwaters; and I hereby declare that the following is a full, clear, and exact description of the same.

This invention relates to a dam, retaining-wall, or breakwater in which the base, the walls for the up and down stream faces, and the cross-walls are of a non-erodic nature to resist the eroding action of the water and are preferably constructed of cement or concrete, so that the entire structure will be a homogeneous unit to allow of the pressure on any part of it being distributed evenly in a greater or less degree to the other parts, the objects of the invention being, first, to so construct the dam, &c., that the sliding and overturning safety factors may be materially increased without necessitating a corresponding increase in the cost of construction; second, to construct the dam of as nearly a uniform cross-section as the special conditions will permit, so as to obtain sufficient strength at the top to act in conjunction with the necessary strength given at the bottom to maintain the alinement of the structure "on plan" throughout its entire length and to insure an equal and uniform strength as opposed to an equal and uniform pressure. These objects are attained by making the dam of a comparatively great width between its upstream and its downstream faces and building up from each edge of the base the wall for the up and down stream faces of sufficient thickness to be stable for the work required of them, such walls being braced at suitable intervals by cross-walls, which form with the walls for the up and down stream faces chambers or cavities to be filled with earth, gravel, broken stone, debris, or, in some cases, water, to increase the total weight of the structure in an inexpensive manner.

For a full understanding of the invention reference is to be had to the following description and to the accompanying drawings, in which—

Figure 1 is a side elevation of the dam, partly in section. Fig. 2 is a plan view of the dam, partly in section. Fig. 3 is a vertical cross-section of the spillway-dam shown in Figs. 1 and 2. Fig. 4 is a vertical cross-section of a dam without a spillway. Fig. 5 is a

vertical cross-section of a modification of the dam shown in Fig. 4. Fig. 6 is a vertical cross-section of a further modification of the construction shown in Fig. 4. Fig. 7 is a vertical cross-section of a modification of the construction shown in Fig. 5, in which the cavity or chamber between the walls of the up and down stream faces is divided by a longitudinal wall extending to the usual cross-walls where such cross-walls occur. Fig. 8 is a vertical cross-section of a spillway-dam utilizing the vertical pressure of the water as a further aid to its stability. Fig. 9 is a vertical cross-section of a dam wherein the water is admitted to the cavity or chamber between the walls for the up and down stream faces. Fig. 10 is a modification of the construction shown in Fig. 9. Fig. 11 is a vertical cross-section of a further modification of the dam shown in Figs. 4 and 6. Fig. 12 is a side elevation, partly in section, of the dam shown in Fig. 10. Fig. 13 is a plan view, partly in section, of the dam shown in Fig. 12. Fig. 14 is a vertical cross-section of a dam constructed on the same principle as the dams shown in Figs. 10, 12, and 13.

Like letters of reference refer to like parts throughout the specification and drawings.

In building the dam an excavation is made to reach the subbase *a*, which must necessarily be of a most stable character, and upon the subbase is laid the base *b* for the dam, retaining - wall, or breakwater, the width of which will depend upon the coefficient of friction of the subbase and the material composing the structure. Extending upwardly from the opposite sides of the base *a* are the face - walls *c* and *d* for the up and down stream faces, respectively, preferably constructed of the same material as the base, which is preferably cement or concrete, so that they will form a homogeneous unit to distribute the water-pressure upon any part of the upstream faces to the other parts of the dam and subbase. The face-walls *d* and *c* are braced at suitable intervals with cross-walls *e*, and between the cross-walls *e* and face-walls *c* and *d* are cavities or chambers *f* to receive an inexpensive filling—such as earth, gravel, broken stone, debris, or, in some cases, water—which will materially increase the width and weight of the dam without adding materially to the cost of its construction. When water is used as a filling for the cavities or chambers *f*, an inlet - opening *g* is formed through the upstream face for each

- cavity or chamber to constitute a means of access between the water in the reservoir and the water in the chamber or cavity between the face-walls, whereby water-pressure may be admitted upon the upper face of the base 5 b in varying degrees according to the depth of the water in the reservoir, so as to correspondingly increase the total pressure of the dam upon the subbase.
- 10 At the ends of the dam are abutments h , integrally formed with the base and the face-walls of the dam, the abutments being constructed, preferably, of the same material as is used in the construction of these parts, and 15 each abutment may be described as consisting of a base i , up and down stream walls j and k , respectively, side walls l , and cross-walls m , interposed between the side walls to form chambers or cavities o , which may be 20 filled with the same kind and quality of filling material as the chambers or cavities between the face-walls.
- Along the faces of the side walls of the abutment adjoining the banks are drain-pipes p , and contained in the dam are drain-pipes q to carry off and deliver downstream 25 the drainage which filters through from the reservoir to insure the filling within the chambers being kept comparatively free 30 from moisture.
- Within the abutments are vertical chambers o' , adjoining the reservoir, fitted with sluice-gates r , through which the water in the reservoir may enter the chambers, such sluice-gates being located as near the bottoms of 35 the chambers as possible to obtain the advantage to be derived from the water being forced under pressure through the sluice-gates into the chambers, and fitted to the 40 chambers o' are tunnels s to carry off the water and deliver it downstream, and thus assist to relieve the flood in the reservoir and reduce the volume of flood-water passing over the spillway.
- 45 Having thus fully described my invention, what I claim as new, and desire to secure by Letters Patent, is—

1. An improvement in dams, retaining-walls and other like structures, comprising a base and vertical face-walls united to the base constructed of non-erosive material, a filling of inexpensive material contained between the face-walls, and abutments at the ends of the face-walls constructed of like material having therein chambers filled with an inexpensive material.
2. An improvement in dams, retaining-walls and other like structures, comprising a base and vertical face-walls united to the base constructed of non-erosive material, a filling of inexpensive material contained between the face-walls, and abutments at the

ends of the face-walls having vertical chambers adjoining the reservoir fitted with sluice-gates, and water-ducks to carry away 65 the water from the chambers to the downstream.

3. An improvement in dams, retaining-walls and other like structures, comprising a base and vertical face-walls united to the base constructed of non-erosive material, a filling of inexpensive material contained between the face-walls, abutments at the ends of the face-walls having vertical chambers adjoining the reservoir fitted with sluice-gates, 70 water-ducks to carry away the water from the chambers to the downstream, and drains along the outer faces of the abutment-walls.

4. An improvement in dams, retaining-walls and other like structures, comprising a base and vertical face-walls united to the base constructed of non-erosive material, a filling of inexpensive material contained between the face-walls, abutments at the ends of the face-walls having vertical chambers 85 adjoining the reservoir fitted with sluice-gates, water-ducks to carry away the water from the chambers to the downstream, and other chambers in the abutments filled with inexpensive material.

5. An improvement in dams, retaining-walls and other like structures comprising a base and vertical face-walls united to the base constructed of non-erosive material, a filling of inexpensive material contained 95 between the face-walls, abutments at the ends of the face-walls having vertical chambers adjoining the reservoir fitted with sluice-gates, water-ducks to carry away the water from the chambers to the downstream, other 100 chambers in the abutments filled with inexpensive material and drains along the outer faces of the abutment-walls.

6. An improvement in dams, retaining-walls and other like structures comprising a 105 base and vertical face-walls united to the base constructed of non-erosive material, the upstream face-wall having inlet-openings through which the water from the reservoir may enter the space between the face-walls.

7. An improvement in dams, retaining-walls and other like structures, comprising a base, vertical face-walls united to the base and cross-walls bracing the face-walls intermediate their ends constructed of non-erosive material, the upstream face-wall having inlet-openings through which the water from the reservoir may enter the space between the face-walls.

Toronto, December 16, A. D. 1904.

JOHN S. FIELDING.
